UNITED STATES PATENT OFFICE

2,104,096

FURNACE

William F. Paradise, Auburn, Nebr.

Application October 6, 1936, Serial No. 104,277

1 Claim. (Cl. 126—99)

This invention relates to a furnace.

An object of the invention is the construction of a furnace that will more efficiently burn the fuel for producing the maximum amount of heat.

Another object of the invention is the construction of a furnace that is provided with a novel flame spreader as well as peculiarly constructed baffles, whereby the burning of the fuel will be efficiently accomplished, for maximum results.

A further object of the invention is the peculiar construction of the smoke conduit, whereby a damper is provided for preventing a flash occurring out of the feed door opening, when fresh coal is fed to the furnace.

With the foregoing and other objects in view, my invention comprises certain novel combinations, constructions and arrangements of parts as will be hereinafter fully described, illustrated in the accompanying drawing, and more particularly pointed out in the appended claim.

In the drawing:

Figure 1 is a view in front elevation, of a furnace constructed in accordance with the present invention.

Figure 2 is a longitudinal sectional view taken on line 2—2, Figure 1, and looking in the direction of the arrows.

Figure 3 is a transverse sectional view, taken on line 3—3, Figure 2, and looking in the direction of the arrows.

Referring to the drawing by numerals, 1 designates the outer shell or jacket and 2 is the inner shell, between which shells or casings a hot air chamber 3 is formed.

A grate 4 is within inner shell 2 and comprises spaced bars 5 with a solid center portion 6. The fire box sides 7, above grate 4, diverge, in cross section, from their upper ends to their lower ends.

A hollow flame spreader 8, in the nature of a table, is placed horizontally within the inner shell 2, and the ends of flame spreader 8 open into the hot air chamber 3 (Fig. 2). The sides of the flame spreader 8 terminate short of the sides 7 of the fire box, whereby there are free passages between the flame spreader and the sides of the inner shell (Fig. 3).

The outer shell 1 is provided with an air-inlet 1a, and any number of hot air-outlets 1b, as may be desired.

The sides of the inner shell 2 are curved inwardly at their upper ends, producing downwardly extending baffles 9, (Fig. 3), which baffles direct the flame more efficiently down upon the fuel that is resting upon the flame spreader 8.

Each baffle 9 extends from the front of the shell

2 to the back of same, as is clearly seen in Figure 2.

A smoke pipe unit is employed in which 10 is the vertical extension that can be connected to any suitable outlet, such as a flue or chimney. 5 At the lower end of extension 10 there are forward and rearward branch pipes 11 and 12, respectively. Each of these branch pipes opens at its lower end into the combustion chamber, formed by the inner shell 2 (Fig. 2). In the 10 front pipe 11 is a manually operated damper 13.

A feed door 14 is placed on the front of the outer shell or jacket 1, and below door 14 is a draft door 15. By means of door 14 the fuel can be placed in the furnace on top of the flame 15 spreader. The furnace can be cleaned of ashes etc., through the door 15.

The purpose of the solid portion 6 of the grate 4 is to retard the burning of coal and to force it to burn on the sides only. The flame spreader 20 8 forces the heat to the sides of the furnace. The fuel used may be nut coal or slack mixture, and when the fuel is coked it will fall down on the grate and then a fresh charge may be placed in the furnace on the flame spreader or table 8 25 to coke. The function of the baffles 9 is to force the heat or blaze down on the coal carried by the flame spreader 8 so as to cause the fuel to coke faster. The object of the damper 13 is to close the front branch pipe 11 when fresh coal is being 30 fed to the furnace, whereby the feeding of the fresh fuel will not cause a flash out the front door.

The hollow spreader 8 increases the amount of radiation, and its open ends allow the hot air 35 to pass into the chamber 3.

The portion of the inner shell to which the inner ends of branch pipes 11 and 12 are connected is in the nature of a dome 16, (Fig. 3). The baffles 9 overhang the flame spreader or table 40 sufficient to cause the flame to be brought close enough to the fuel on the flame spreader to efficiently coke the fuel.

When fresh coal is put in the furnace on the grate and the draft is open, it will burn up so 45 vigorously that the flame will go up the sides and around the baffles 9; then, if the draft is closed, the gas in the whole furnace becomes stagnant, to a certain extent. If the gas trapped under baffles 9 is inflammable, it will burn out (see Fig. 3 50 of the drawing) and let other gases flow in resulting in the heating of baffles 9 and they in turn will transfer the heat to the compartment or air chamber between the inner and outer shells.

While I have described the preferred embodiment

ment of my invention and illustrated same in the accompanying drawing, certain minor changes or alterations may appear to one skilled in the art to which this invention relates during the 5 extensive manufacture of same and I, therefore, reserve the right to make such alterations or changes as shall fairly fall within the scope of the appended claim.

What I claim is:

- 10 10 In a furnace, the combination of an inner and outer shell having parallel longitudinally-extending side walls, said shells being spaced apart to form an air chamber therebetween, a grate in the inner shell, a fuel spreader within the inner shell, said spreader being spaced above said grate
- 15

and from the longitudinal walls of the inner shell, an opening in the inner shell above the spreader through which fuel is placed on the spreader or permitted to fall therefrom to the grate, the longitudinal side walls of said inner shell having 5 their top portions inwardly curved, longitudinal baffle members overlying said spreader and integral with said top portions, said members being spaced apart and forming downward continuations of the curved top portions whereby to 10 direct downwardly towards the fuel on said spreader the hot gases arising between the spreader and side walls, and a flue outlet between the baffle members at the top of the inner shell.

WILLIAM F. PARADISE. 15
